(57) **CLAIM**

The ornamental design for a cutlery stand set as shown and described.

DESCRIPTION

FIG. 1 is a Top Front Right Side Isometric view of the cutlery stand set;
FIG. 2 is a Bottom Rear Left Side Isometric view thereof;
FIG. 3 is a Front Elevation view thereof;
FIG. 4 is a Rear Elevation view thereof;
FIG. 5 is a Left Elevation view thereof;
FIG. 6 is a Right Elevation view thereof;
FIG. 7 is a Top Plan view thereof;
FIG. 8 is a Bottom Plan view thereof;
FIG. 9 is a Top Front Right Side Isometric view of the Stand, shown separately for the ease of illustration;
FIG. 10 is a Bottom Rear Left Side Isometric view thereof;
FIG. 11 is a Front Elevation view thereof;
FIG. 12 is a Rear Elevation view thereof;
FIG. 13 is a Left Elevation view thereof;
FIG. 14 is a Right Elevation view thereof;
FIG. 15 is a top plan view thereof;
FIG. 16 is a Bottom Plan view thereof;
FIG. 17 is a Top Front Right Side Isometric view of the Fork, shown separately for the ease of illustration;
FIG. 18 is a Bottom Rear Left Side Isometric view thereof;
FIG. 19 is a Front Elevation view thereof;
FIG. 20 is a Rear Elevation view thereof;
FIG. 21 is a Left Elevation view thereof;
FIG. 22 is a Right Elevation view thereof;
FIG. 23 is a Top Plan view thereof;
FIG. 24 is a Bottom Plan view thereof;
FIG. 25 is a Top Front Right Side Isometric view of the Knife, shown separately for the ease of illustration;
FIG. 26 is a Bottom Rear Left Side Isometric view thereof;
FIG. 27 is a Front Elevation view thereof;
FIG. 28 is a Rear Elevation view thereof;
FIG. 29 is a Left Elevation view thereof;

(Continued)

FIG. 30 is a Right Elevation view thereof;
 FIG. 31 is a Top Plan view thereof;
 FIG. 32 is a Bottom Plan view thereof;
 FIG. 33 is a Top Front Right Side Isometric view of the large Spoon, shown separately for the ease of illustration;
 FIG. 34 is a Bottom Rear Left Side Isometric view thereof;
 FIG. 35 is a Front Elevation view thereof;
 FIG. 36 is a Rear Elevation view thereof;
 FIG. 37 is a Left Elevation view thereof;
 FIG. 38 is a Right Elevation view thereof;
 FIG. 39 is a Top Plan view thereof;
 FIG. 40 is a Bottom Plan view thereof;
 FIG. 41 is a Top Front Right Side Isometric view of the small Spoon, shown separately for the ease of illustration;
 FIG. 42 is a Bottom Rear Left Side Isometric view thereof;
 FIG. 43 is a Front Elevation view thereof;
 FIG. 44 is a Rear Elevation view thereof;
 FIG. 45 is a Left Elevation view thereof;
 FIG. 46 is a Right Elevation view thereof;
 FIG. 47 is a Top Plan view thereof; and,
 FIG. 48 is a Bottom Plan view thereof.
